Primary Examiner—Susan J. Lucas*Assistant Examiner*—Cynthia E. Ramirez*Attorney, Agent, or Firm*—Shook, Hardy & Bacon L.L.P.[57] **CLAIM**

The ornamental design for a liquid applicator body, as shown and described.

DESCRIPTION

FIG. 1 is a top perspective view thereof;

FIG. 2 is a bottom perspective view thereof;

FIG. 3 is a front elevational view thereof, the rear elevational view being identical thereto;

FIG. 4 is a top plan view thereof; and,

FIG. 5 is a right end elevational view thereof, the left end elevational view being identical thereto.

The broken line showing of a porous element attached to the bottom surface of the liquid applicator body in FIGS. 1, 3, 4 and 5, and of the bottom surface of the liquid applicator body in FIG. 2, are for illustrative purposes only and do not form a part of the claimed design.

1 Claim, 2 Drawing Sheets*FIG. 1.*

FIG. 2.

*FIG. 4.**FIG. 5.*
